SHOE PARTS PRESS

Filed April 24, 1937

UNITED STATES PATENT OFFICE

2,224,612

SHOE PARTS PRESS

John Frederick Smith, Quincy, Mass., assignor to
 Compo Shoe Machinery Corporation, New York,
 N. Y., a corporation of Delaware

Application April 24, 1937, Serial No. 138,735

2 Claims. (Cl. 12—17)

This invention relates to presses for use in attaching together elements of a shoe bottom assembly such as those disclosed in the copending applications of Henry B. Gorman, Serial

5 Nos. 50,070 and 122,501, filed November 16, 1935, and January 27, 1937, respectively, useful in the making of certain types of welted shoes, e. g., those disclosed in the copending application of Henry B. Gorman, Serial No. 38,685 filed August

10 31, 1935.

An object of the invention is to provide a press for such purposes which is capable of being rapidly and efficiently loaded and unloaded, is exceptionally well suited for applying pressure

15 to elements of a shoe bottom assembly while they are being cemented together, is simple in construction and capable of being economically manufactured and which is particularly well adapted to be used with a carrier or continuous

20 conveyor of known type wherein provision preferably is made for successively opening automatically a series of presses to allow loading and for applying pressure to the presses and releasing it therefrom in accordance with a predetermined plan of operation.

Other objects of the invention will in part be obvious and will in part appear hereinafter.

The invention accordingly comprises the features of construction, combination of elements, 30 and arrangement of parts, which will be exemplified in the construction hereinafter set forth and the scope of the invention will be indicated in the claims.

For a fuller understanding of the nature and 35 objects of the invention reference should be had to the following detailed description taken in connection with the accompanying drawing, in which:

Fig. 1 is a diagrammatic plan view of a portion 40 of a carrier showing a plurality of presses of the present invention located thereon at the deflating station, release station, loading station and in the inflating zone;

Fig. 2 is an end elevational view of a preferred form of the press of the present invention; and

Fig. 3 is a sectional view taken on line 3—3 of Fig. 2.

In accordance with the inventions disclosed in 50 the previously mentioned applications of Henry B. Gorman, it is contemplated that a shoe bottom assembly may be cemented to a lasted upper, the shoe bottom assembly comprising a welt unit or ply and an outsole cemented or stitched thereto. 55 The welt ply may consist of a welt, a fastening

strip and a shaping piece or filler as disclosed in the Gorman application Ser. No. 122,501. When a cement bond is to be employed between the welt unit or ply and the outsole, some means is needed to hold them in proper position with respect to each other and to subject them to a pressing operation while the cement sets. In accordance with the present invention a press of simple and efficient construction is provided for holding the welt unit or ply and the outsole in registry and pressing them together.

Referring more particularly to the drawing, there is shown in Figs. 2 and 3 a press adapted for this purpose. This press comprises a pair of opposed platens hinged together, one of said platens being spring biased with respect to the other in a manner so that except when they are locked together in pressing position the pressing surfaces are separated to allow loading and unloading. Releasable means are provided to lock the platens together in pressing position and in the preferred form the pressing surface of at least one platen is fitted with a resilient pad to accommodate a shank-skived or otherwise irregularly surfaced (but substantially flat and unmolded) outsole and/or welt unit or ply.

The preferred embodiment of the invention shown in the drawing comprises a base member 10 having a recess 11 in the upper face thereof in which is located a resilient pad 12 of suitable 30 construction, preferably a hollow inflatable pad provided with a substantially flat upper surface 13 and consisting of a rubber bag 14 covered with a casing 15 of any suitable material such as leather. A depending portion 16 at the rear 35 end of the base member 10 is apertured to receive an inflating and deflating conduit 17 suitably connected to and communicating with the interior of the inflatable pad 12. The conduit 17 terminates in a valve 18 having a projecting plunger 19 for unseating the valve.

An upright arm 20 is mounted, preferably integrally therewith, upon the rear end of the base member 10. A movable rigid platen 21 having a substantially flat pressing surface 22 45 is pivotally mounted upon the arm 20 by means of a horizontally disposed pintle 22 extending through a pair of apertured knuckles 23, 23 on the platen 21 and through a hole in the arm 20. Such a platen is fitted to care for substantially 50 flat bottom assemblies involving use of a flat outsole. If a molded outsole, or other somewhat irregular type of work were to be used, the platen 21 and the pad may have complementary or mutually conformable surfaces.

An upstanding extension or forked post 24 is secured to the upright arm 20 by a pair of bolts such as 25, extending through the ends of the base 26 of the extension 24 and threaded into the arm 20. The forked extension 24 terminates at its upper end in a pair of spaced tines 21, 27 apertured to receive a pin 28. Upon the platen 21, preferably on the upper side and centrally, is located an ear 29. A coil spring 30 has one end connected to the ear 29 and the other end connected to the pin 28 mounted upon the upstanding extension 24 to bias the platen 21.

A projection is provided on the front end of the platen 21 to cooperate with a latch member on the base member 10. This projection preferably comprises a pair of spaced knuckles 31, 31 formed integrally with the platen and apertured to receive a horizontally disposed rod 32. A cooperating latch structure on the base 10 comprises a pair of spaced knuckles 33, 33, preferably made integrally with the base, apertured to receive a horizontally disposed pintle 34 extending through a latch member 35 positioned therebetween. The latch member 35 is provided with an upwardly extending hooked portion 36 having a nose 37 adapted to engage over the rod 32 on the platen 21 and lock the latter in pressing position.

A stop 38 on the latch 35 cooperates with an upper surface of the front edge of the base member 10 to limit the counterclockwise movement of the latch member 35 as viewed in Fig. 3. The latch member 35 extends below the pintle 34 to form a latch finger 39 against which presses a plunger 40 backed by a coil spring 41 located in a bore 42 in a boss 43 formed on the under side of the base member 10. The spring acts to bias the latch member 35 and hold it normally in latching position. The latch finger 39 also serves as a releasing finger, as will be explained.

In the preferred construction shown in the drawing the platen 21 is provided with strengthening webs 44, 44 extending along the sides thereof and webs 45, 45 each extending from one of the knuckles 31, 31 to the rear end as shown. The base member 10 is provided with strengthening and supporting webs 46, 46 extending downwardly from the sides thereof and additional strengthening webs 47, 47 each extending from one of the knuckles 33, 33 to the rear end thereof which may additionally serve as supporting means adapted to engage the surface of a carrier belt. Threaded apertures 48, 48 are provided in the front and rear ends of each of the webs. A threaded bolt 49 is mounted in the hole 48 in the rear end of the web 46 and carries an internally threaded headed collar 50. A threaded stud 51 is mounted in the hole 48 in the front end of the web 46. The shanks of the collars 50, 50 and the studs 51, 51 are adapted to be received in slots in upstanding press supporting lugs on carrier cleats (not shown) of known or suitable form to bolt the press to the movable carrier.

In operation a plurality of presses of the present invention are mounted upon a carrier 52, a portion of which is indicated in dotted outline in Fig. 1. Preferably the carrier is of the continuous conveyor type shown in my copending application Ser. No. 36,053, filed August 14, 1935, although other known or suitable conveyors or turret carriers may be used. When used in attaching together elements of a shoe bottom assembly of the type disclosed in the mentioned Gorman application Ser. No. 122,501, a welt ply comprising a welt unit having its fastening strip sewed to a shaping piece or filler, and a prepared

outsole are cemented together in the following manner.

The welt ply is located adjacent the outsole in a registered position with the outer edges of the welt registered with the rounded edges of the outsole and a preliminary locating adhesive may be applied between the extreme rear portion of the welt ply and the outsole in order to hold the former in registered position. A strong permanent adhesive such as pyroxylin cement is interposed between the welt ply and the outsole. This cement may be applied to the welt and/or the shaping piece prior or subsequent to the construction of the welt ply and/or may be applied to any desired portions of the outsole. In each instance it may be applied wet just before assembly of the elements of the shoe bottom assembly or previously and permitted to dry and then rendered adhesive by the application of solvent just prior to assembly of the elements.

The welt ply and an outsole having permanent adhesive in an adhesive condition therebetween are located by the operator in registry of one of the presses of the present invention positioned at the loading station, preferably with the welt ply side of the shoe bottom assembly positioned against the resilient pad 12. The platen 21 is swung down until the nose 37 of the latch member 35 engages over the rod 32 on the platen thereby locking the platen to the base member 10 in pressing position. A movable air supply chuck 53 of known construction mounted upon a carriage (not shown, but preferably of the kind shown in my mentioned application Serial No. 36,053) is engaged with the valve 18 at the loading station and a pick-up lug 54 on the base member 10 engages a portion of the carriage to carry along the chuck 53 through the inflating zone. Chuck 53 is then disengaged from the valve 18 and the press is 40 routed around the carrier while the cement sets. The loaded press then approaches the deflating zone where a deflating plunger 55 engages the detent 19 of the valve 18 and holds the valve open while inflatable pad 12 deflates. The press 45 then approaches a release station where a fixed unlatching cam 56 engages the latch finger 39 allowing the platen 21 to be released and swung upwardly by the spring 30. The press then proceeds to the loading station where it is unloaded 50 and reloaded with another shoe bottom assembly unit and the operation is repeated with each of the plurality of presses located on the carrier. The assembled welt ply and outsole may then be removed from the press and molded or otherwise suitably prepared for attachment to a lasted upper.

Variations in the type of support or carrier for the press, in the nature of the pressure applying pad, in the types of cement employed, etc., 60 may obviously be made without departing from the scope of the described invention.

It will thus be seen that the objects set forth above are efficiently obtained and since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of

the invention which, as a matter of language, might be said to fall therebetween.

Having described my invention, what I claim as new and desire to secure by Letters Patent, is:

- 5 1. A press for use in attaching together elements of a shoe bottom assembly comprising a base member having a recess in the upper face thereof, supporting means on the under side thereof, a substantially flat pressure applying 10 pad located in the recess, an inflating medium conduit mounted on said base member connected to said pad and terminating in a valve projecting at one end of said base member to cooperate with an inflating chuck and a pressure releasing device, a rigid upright arm mounted on the same end of said base member, a rigid substantially flat platen pivotally mounted on said arm by a horizontally disposed pintle, an upright extension mounted on said arm, a spring-engaging 15 20 25 ear on said platen, a coil spring connected between said extension and said ear to hinge said platen away from said pad to allow loading and unloading, a projection on the end of said platen opposite the end pivotally mounted on said arm, a latch hook pivotally mounted on the other end of said base member to engage said projection to lock said platen in pressing position adjacent
- 5 said pad, a spring normally holding said latch hook in latching position, and a projection on said latch hook to cooperate with releasing means mounted on a carrier frame.
2. In a machine for pressing shoe bottom assemblies, a carrier movable along a path, a press on said carrier having a pocketed base, a leather encased inflatable pad in said pocket presenting a substantially flat flexible upper diaphragm, a fluid conduit leading to said pad having inflating 10 and deflating valve means therein, an arm extending upwardly from said base at one end thereof, a rigid platen forming a lid over said base and having a substantially flat work engaging face overlying said diaphragm, said platen being hinged to said base at the end thereof bearing said arm, a spring between said arm and platen normally urging the latter upwardly to open position, a latch hook for holding said platen and base closed together with work therebetween, a projection on said latch hook to cooperate with releasing means along said carrier path, means along said carrier path to operate said valve to inflate and deflate said pad, and means along said carrier path to release said 15 20 25 latch projection.

JOHN FREDERICK SMITH.
